UNITED STATES PATENT OFFICE.

MARSHALL M. KIRKMAN, OF EVANSTON, ILLINOIS.

FREIGHT-RECORD.

SPECIFICATION forming part of Letters Patent No. 388,881, dated September 4, 1888.

Application filed May 29, 1888. Serial No. 275,526. (No model.)

To all whom it may concern:

Be it known that I, MARSHALL M. KIRKMAN, a citizen of the United States, residing at Evanston, Cook county, Illinois, have invented certain new and useful Improvements in Freight-Records, of which the following is a specification.

The object of my invention is to make a system of freight-records whereby at one operation there may be filled out all of the necessary blanks required to notify the consignee of the arrival of goods and the charges thereon and such other information as may be desired, the receipt which the railroad company takes from the consignee upon the delivery of the goods, the receipt which the railroad company gives, order upon the foreman of freight-house where goods are in store, receipt of teamster, and such other matters as may enter into the transaction; and my invention consists of the features and details of construction, hereinafter described and claimed.

In the drawings, Figure 1 represents the plan view of a blank for the expense-bill which is signed by the railroad company and given the consignee upon payment of charges, &c.; and Fig. 2, a plan view of another blank form, the receipt which the carrier takes upon the delivery of the goods. Both of these figures are made with the blank torn in two, as the full length would be too great for continuous representation.

In making my improved system of freight-records for railways, steamboats, and other common carriers where goods are conveyed and charges collected I make a series of printed blanks, which are intended to be filled out by the same operation or writing. One of these blanks, as shown in Fig. 1, may be an expense-bill provided with proper headings and having blanks for the insertion of the name of the consignor, the consignee, the articles, and the charges on the same, with other particulars, and for the receipt for the said charges by the agent, so that the same, when properly filled out, shall form a complete expense-bill and receipt to the consignee. Another of these blanks, like that shown in Fig. 2 of the drawings, is provided with similar headings and blanks, in which may be inserted the names of the consignor and the consignee, the articles and the charges, and the consignee's re-

ceipt, and such other matter as may be necessary for forming a complete record of the freight received from the company and the taking of 55 the consignee's receipt for the same.

Although I have only shown in the drawings a series of two blanks, others may be formed in a similar way, with headings and spaces so placed on the blanks that when the 60 name of the consignor and the consignee, &c., shall be written in the completed blank shall form an order upon the foreman of the freight-house to deliver the goods in his possession to the consignee, or a notice to the consignee of 55 the arrival of such goods. These blanks, after being so printed, may be bound in succession in the form of books or blocks or otherwise, as may be desired, so that a way-bill may come first, then expense-bill, beneath that the receipt for goods, beneath that the order on the freight-house man, and beneath that the notice to the consignee, and so on, the blanks in the different forms and the headings of the columns coming immediately below the similar blanks 75 and headings of the columns on the first form. It is not necessary that these blanks should be bound in precisely the order named, as they may be bound in any other order desired, my invention being that they shall be so arranged 80 beneath one another that the columns, headings, and blanks shall coincide, so that the writing which is afterward inserted may fall in its proper place in each blank. Although I have claimed these blanks as bound in book 85 form, it is obvious that, if desired, they may be bound in blocks or in any other suitable manner.

There may be but a single expense-bill to the page; or they may be bound up similarly to the 90 ordinary check-book used by banks, with three or four or more on a page, provided with suitable perforations for tearing out the same.

The method of using my improved system is as follows: Blanks having been printed and 95 bound in series in a book, the ordinary carbon-paper is inserted between each of the pages, by which whatever is written upon the first page will be transferred to each of the succeeding pages. The agent then writes in the spaces 100 of the first form the name of the consignor and consignee, the character of the articles and the charges upon the same, and other particulars. The matter so written in being transferred by

the action of the carbon-paper to each of the succeeding sheets, there will be formed a complete expense-bill, which may be given to the consignee as a receipt, an order on the freight-house foreman, which is given to the consignee, and the receipt for the goods, which is retained by the company and is signed by the consignee when the goods are removed by him, and such other forms as it may be desirable to use.

Although I have called my invention an "improved system of freight-records" and have described it as such, it is not my intention to limit myself to this use alone, as it is obvious that this is only one of the many uses to which my invention can be applied. For instance, the entire accounts of a railroad or other common carrier, which require the formation of a series of blanks differing in the printed matter, but similar in that to be written in, may be kept in this manner. So with any other of the transactions of railroads, other common carriers, or commercial houses, the purpose of my invention being to provide such

a series of blanks so printed that when the same are filled up by written matter they shall form two or more forms complete in themselves, but differing from each other, requiring in some instances trifling details to be inserted afterward to make them complete.

I claim—

A freight-record blank book or block comprising complete record sets of detachable sheets having on one side printed matter and blank spaces in columns, each set comprising one or more detachable sheets and one permanent sheet, and all arranged so as to have the special printed matter and blank spaces in the columns thereof in alignment, so that the matter written in the spaces on the top sheet of the set will be simultaneously transferred by means of interposed carbon-sheets to its proper place on the other sheets of the set, substantially as shown, and for the purpose described.

MARSHALL M. KIRKMAN.
